UNITED STATES PATENT OFFICE.

HAROLD CUSACK, OF CHICAGO, ILLINOIS, ASSIGNOR TO THE THOMAS CUSACK COMPANY, OF CHICAGO, ILLINOIS, A CORPORATION OF NEW JERSEY.

HEAD-PLATE FOR SIGN-BOARDS.

1,256,523.

Specification of Letters Patent.

Patented Feb. 19, 1918.

Application filed May 5, 1917. Serial No. 166,511.

To all whom it may concern:

Be it known that I, HAROLD CUSACK, a citizen of the United States, and a resident of Chicago, in the county of Cook and State of Illinois, have invented certain new and useful Improvements in Head-Plates for Sign-Boards; and I do hereby declare that the following is a full, clear, and exact description thereof, reference being had to the accompanying drawings, and to the letters of reference marked thereon, which form a part of this specification.

This invention relates to an improved headplate for signboards and consists of the matters hereinafter described and more particularly pointed out in the appended claim.

In the case of all signboards, bulletin boards or other advertising boards, it is customary and desirable for the proprietor and lessor of the board, who is also usually the one that applies the advertising or other matter to the board for the lessee, to show his own name on a name plate, either separate from, or made a part of the board, to identify both his ownership of the board, and also the origin of the work on the board as in himself.

Various means have been employed to this end, but all those heretofore used have been objectionable for one reason or another.

The object of the present invention is to provide a head plate adapted to bear the name of the lessor or the one owning the board, which is not only cheap and economical in construction, but which may be readily and easily applied to any board, so that a stock of head plates may be kept on hand to replace those which are marred or worn.

The advantages of my invention will appear as I proceed with my specification.

In the drawings:

Figure 1 is a front view of a signboard provided with my improved head plate.

Fig. 2 is a view in rear elevation of the same.

Fig. 3 is a view representing a vertical section through the board, in a plane indicated by the line 3—3 of Fig. 2.

Referring now to that embodiment of my invention illustrated in the drawings:—10 indicates the signboard, and 11 indicates the improved head plate. The head plate is preferably made of enameled sheet metal, and bears the name of the lessor or proprie-

tor of the board, which is put on the head plate during or in the process of enameling. A head plate of this kind may be made with economy, of the required rigidity and strength, and at the same time of a handsome and attractive appearance. In addition, being of enameled ware, it has endurance against the wear of rain and snow and of other weather conditions.

The signboard 10 is provided with two or more, preferably two, upright, flat bars 12, 12 which are attached to it by screws, bolts or otherwise. These bars are permanently fixed and may be placed at a standard distance apart on every board owned or controlled by the proprietor or lessor.

Upon the rear face of the head plate are fixed horizontally spaced sets of straps 13, 14,—the straps of each set being in vertical alinement and being adapted for engagement with one of the bars 12 on the sign board. The sets of straps are spaced at a horizontal distance apart corresponding to such standard distance between the upright bars on the signboard as may be determined upon.

Of the straps 13, 14 of a set, one, namely the top one, is provided with a horizontal shoulder or stop 15 to engage the top of the associated bar 12. The other strap or straps 13 provides merely a slot for engagement with the bar 12. A set screw 16 is threaded into the strap 13 for engagement with the associated bar 12 in order to hold the head plate upon the associated bars.

The advantages of the construction will be apparent from the foregoing description. If the head plates wear out or become discolored or distorted, they are easily replaced by the proprietor or lessor from a stock on hand. As the headplates may be made in quantities and of standard sizes, and as the bars 12 are all fixed to the signboards at standard distances apart, it is manifest that a headplate may be replaced with much greater economy than if it were necessary to repaint the sign on the signboard itself, or upon a separate board fixedly attached to said signboard.

I claim as my invention:

A head plate for sign boards of the kind described, comprising in combination with a board, upright bars attached to said board and spaced at a standard distance apart, a head plate provided with sets of straps

105

110

spaced at a standard distance apart equal to the distance between the said bars, the straps of each set being arranged in vertical alinement and adapted for engagement with an associated bar, and one of said straps being provided with a stop to engage the top end of its associated bar.

In testimony that I claim the foregoing

as my invention I affix my signature in the presence of two witnesses, this 20th day of 10 April, A. D. 1917.

HAROLD CUSACK.
